DESIGN FOR A PAPER ROLL HOLDER OR SIMILAR ARTICLE

Frederick Bletzinger, Sr., Chicago, Ill.

Application January 24, 1947, Serial No. 136,371

Term of patent 14 years

(Cl. D74—1)

To all whom it may concern:

Be it known that I, Frederick Bletzinger, Sr., a citizen of the United States, residing at Chicago, in the county of Cook and State of Illinois, have invented a new, original, and ornamental Design for a Paper Roll Holder or Similar Article, of which the following is a specification, reference being had to the accompanying drawing, forming a part thereof.

Figure 1 is a perspective view of a paper roll holder or similar article, showing my new design.

I claim:

The ornamental design for a paper roll holder or similar article, as shown.

FREDERICK BLETZINGER, SR.
